CLAIM

The ornamental design for a foot sleeve with bunion cushion, as shown and described.

DESCRIPTION

FIG. 1 is a perspective view of a foot sleeve with bunion cushion showing my new design in condition of use on a human foot;

FIG. 2 is a front view of my new design;

FIG. 3 is a top view thereof;

FIG. 4 is a right side view thereof;

FIG. 5 is a rear view thereof;

FIG. 6 is a left side view thereof; and,

FIG. 7 is a bottom view thereof.

The broken lines in FIGS. 1-7 illustrate portions of the foot sleeve with bunion cushion and environmental structure which form no part of the claimed design.
